UNITED STATES PATENT OFFICE.

CARL F. LAUBER, OF PHILADELPHIA, PENNSYLVANIA.

DESIGN FOR A DISH.

SPECIFICATION forming part of Design No. 14,609, dated February 5, 1864.

Application filed October 12, 1863. Term of patent 14 years.

To all whom it may concern:

Be it known that I, CARL F. LAUBER, a citizen of the United States, residing at Philadelphia, in the county of Philadelphia and State of Pennsylvania, have invented and produced a new and original Design for a Dish, of which the following is a specification, reference being had to the accompanying drawings.

In the accompanying drawings, Figure 1 is a plan view of my newly-designed dish with the perforated plate removed. Fig. 2 is a plan view of the perforated plate. Fig. 3 is a vertical central section thereof and of the dish.

Similar letters indicate corresponding parts.

15 In the drawings, the letter A indicates the central portion or body of the dish, the sides or wall of said body being of rounded or bulging form. This dish is provided with a ledge or shoulder, D, upon which the perforated plate B is made to rest.

C indicates a rim or flange, of curved or flaring form, so as to cause any article which falls upon said flange to drop toward the central portion of the dish.

25 The plate B is provided with perforations F, which perforations consist, approximately, of quadrangulated quarter-circles, so as to cause said perforations to assume a scalloped or epicycloidal form, thus presenting an ornamental appearance. Additional perforations may be made in the plate, if desired, as shown in the drawings.

A base or rim, E, may be provided for the article to stand upon, thus causing it to rest firmly.

It will be seen that between the plate B and the bottom of the dish is a space in which fluid may settle.

The plate B may be readily taken out, and the various parts can be easily cleaned.

I am aware that in such articles as butter-dishes perforated plates have been caused to rest on ledges or shoulders formed in a dish, and it is not intended herein to broadly claim such arrangement.

What I claim as new, and desire to secure by Letters Patent, is—

1. The design for a dish herein shown and described, the same consisting of a curved rim or flange, C, a shoulder or ledge, D, and a rounded or bulging body, A, in combination with a plate having epicycloidal or scalloped openings.

2. In the design for a dish-plate herein shown and described, the scalloped or epicycloidal openings wholly within the outline of the edge of the plate.

In testimony whereof I have hereunto set my hand and seal in the presence of two subscribing witnesses.

CARL F. LAUBER. [L. S.]
